F. D. BLESSMEYER,
INVENTOR.

BY William A. Cottle,

ATTORNEY.

UNITED STATES PATENT OFFICE.

FRED D. BLESSMEYER, OF PITTSBURGH, PENNSYLVANIA.

STABILIZING DEVICE.

1,327,586.

Specification of Letters Patent.

Patented Jan. 6, 1920.

Application filed November 30, 1918. Serial No. 264,822.

To all whom it may concern:

Be it known that I, FRED D. BLESSMEYER, a citizen of the United States of America, residing at Pittsburgh, in the county of

5 Allegheny and State of Pennsylvania, have invented certain new and useful Improvements in Stabilizing Devices, of which the following is a specification.

The present invention relates to stabilizing devices used as supports in electric cars, and similar conveyances, and has for its purpose the provision of new types of stabilizers or hangers with pertinent operating parts possessing the following advantages.

15 By the arrangement of parts and devices of my new device, the loading and unloading of passengers into and out of the vehicle or car is greatly accelerated; all the available "standing room" or space is placed under 20 the immediate control of the employees operating the car, thus enabling all the space of this character to be used in every car; and a rigid support or stabilizer is provided for passengers, each stabilizer when not in 25 use automatically retiring to an out of the way position as will least obstruct the interior head-room space of the conveyance. All of these advantages and others will be 30 hereinafter more particularly explained as the description contained in this specification proceeds.

In the accompanying drawings forming part of this specification, I have shown one complete example of the physical embodiment of my invention, and a modification thereof, constructed according to the best mode I have so far devised for the practical application of the principles of my invention.

40 Figure 1 of the drawings is a front view of one of the types of stabilizer or hanger forming part of my invention, one of the hangers being shown in section.

Fig. 2 is a transverse view of the type of 45 stabilizer shown in Fig. 1, illustrated in operative position within an electric car.

Fig. 3 is a view similar to Fig. 2 of the preferred type of stabilizer shown in Figs. 5 and 6.

50 Fig. 4 is a front view of the longitudinal supporting rod of an electric car with my invention in operative position thereon.

Fig. 5 is an enlarged front detail view, partly in section of the type of stabilizer shown in Figs. 3 and 4.

55 Fig. 6 is a transverse side view partly in

section taken from the right of Fig. 5, the spiral spring not being shown in the Fig. 6.

Fig. 7 is a plan view of the hanger shown in Fig. 5.

Fig. 8 is a diagrammatic view of a "center entrance" electric car with my invention shown therein.

Fig. 9 is a similar diagrammatic view of my invention arranged for use in an "end entrance" electric car.

In the drawings Figs. 3 to 7 inclusive illustrate the preferred form of my invention, and Figs. 1 and 2 the modified form of same.

The preferred form of the invention will be first described, in which 1 indicates a longitudinal and preferably hollow metal supporting rod, somewhat similar to the wooden rod at present in electric cars, having the 75 holders 2, 3 at intervals, for attachment to the roof of the car or conveyance 4. The tubular member 1 is rotatably mounted in the holders 2, 3, etc., and longitudinal displacement of the member or rod 1 is prevented by the use of the annular collars 5, 6, etc., which last are rigidly mounted on the rod 1 on each side of the holders 2, 3, etc., as shown.

The hanger or stabilizer or hanger proper 85 consists of a preferably hollow metal pipe 7, screw-threaded at both ends 8, and 9, to accommodate the complementary threads of the handle 10, and the cap 11 respectively. The construction of the handle 10 and cap 90 11 is shown in Figs 5 and 6. The cap 11 has a downwardly curved annular rim 12, adapted to receive the top coil 13 of a spiral spring 14, and also a projecting flange 15 engaging the threaded end 9 of 95 the pipe 7. An annular collar 16 encircles the end 9 of the pipe 7, either rigidly mounted thereon, or formed integral therewith, for a purpose described below. A metal casting 17 having a curved upwardly 100 turned rim 18 adapted to receive the lowermost coil 19 of the spring 14, and a tubular projection 20 is rigidly mounted on the longitudinal rod 1. The tubular portion 20 of the casting 17 passes through the rod 1 105 as shown in Figs. 5 and 6. In plan view it is seen the casting 17 is preferably other than circular in shape as illustrated in Fig. 7, so that when the handle 10 is turned around or revolved about the vertical axis 110 of pipe 7, the spring 14 will meet with resistance to being turned, by the flattened

110

sides 21 of the rim 18, thereby preventing disarrangement of the device by any person tampering with the handle 10. The casting 17 is preferably made with a raised or 5 bossed annular shoulder 22, so that when the handle 10 is drawn downward to position 23, Fig. 4, the downward pull by the user of the device is not resisted by the coils of the spring 14, but the lower edge 10 of the annular collar 16 engages against said shoulder 22, making a rigid or non-elastic support. Moreover it is seen that the spring 14 can thereby be made much less in strength, when this form of construction is used, because the spring is not 15 designed to resist the weight of the person, its function being principally to return the unloaded handle 10 automatically to its uppermost position as shown in the Fig. 5. 20 The coils of the spring 14 when same is compressed fit within each successive neighbor, as is readily understood, and rest on the face 24 of the casting 17, and the spiral tapered type of spring as shown in Fig. 5. 25 25 is used for this reason in preference to a cylindrical coiled spring, like that shown in the Fig. 1 of the drawings. The rim 18 is flattened at 21 on each side of the casting 17 so that the projections of the rim as 30 shown in the Fig. 6, will form as small obstructions as may be possible transversely beyond the sides of the longitudinal member or rod 1. The pipe 7 reciprocates vertically in the part 20 of the casting 17, 35 when the handle 10 is drawn downward by the user of the device and the spring 14 automatically retracts the handle to its highest position close to the rod 1, the moment the handle is released by the user. A 40 rigidly mounted collar 92 on the pipe 7 forms a "stop" for the handle 10 in its upward travel, and in order to eliminate noise and reduce the shock when the handle returns to the retracted position shown in 45 Fig. 5, a fiber or leather washer 93 is provided, which engages between the collar 92 and the lower end 94 of the pipe 7.

On the ends of the longitudinal member or rod 1, a special holder 25 is used, which 50 performs a double function of a support and a part of the locking mechanism of the device. Figs. 3 and 4 illustrate this feature best. A lever 26 is rigidly mounted on rod 1, and is provided with a projection 27 55 which can be beveled at 28 if desired to more readily engage in the slots 29, 30, etc. formed in the arc-plate portion 31 of the special holder 25. The handle 32 enables the metal lever 26 which possesses the necessary resiliency to be "sprung" out of one slot such as 29, and moved around to another slot such as 30 when desired. From 60 which it is seen that while the hanger or stabilizer 33 and lever 26 are rigidly mounted on the rod 1, that by operating the

handle 32 the pipe or rod 1 itself can be rotated in its holders 2, 3, etc., thereby throwing the stabilizer 33 to the position shown dotted at 34 in Fig. 3. When the stabilizer is in position 34, it is out of the way, and causes less obstruction in the head-room space of the car or other conveyance. This lever 26 as will be shown is placed under the control of the employees of the car, thereby controlling the proper loading of the car. As many stabilizers 33 can be used as necessary and levers 26 with accompanying parts can be placed on each of the ends of the rod 1, when found to be desirable. So that not only do the handles 10 of each stabilizer on each rod 1 automatically retract when not in use, but the conductor or other employee of the car can control a series of stabilizers on each separate longitudinal rod 35, 36, to 42 inclusive. (See Figs. 8 and 9 of the drawings.)

In the modification of my invention shown in Figs. 1 and 2, I have shown another type of stabilizer which can be used as an alternative to that first described. In the modification 43 indicates a longitudinal tubular member like 1 of the Fig. 4, 44 is a vertically disposed preferably hollow pipe having screw-threaded ends at 45, 46 for receiving the complementary threaded handle 47 and cap 48. A hollow socket 49, preferably of cast metal as shown in Fig. 1, having chambers 50 and 51 of different internal dimensions, is rigidly mounted in the 95 tubular member 43. The chamber 51 is of proper diameter to slidably receive the hollow pipe 44, while the chamber 50 is made large enough to freely accommodate the cylindrical spring 52 when it is in compressed position. The cap 48 is provided with downwardly projecting screw-threaded flange 53 having threads engaging the end 46 of pipe 44, before described, and said cap has also the outwardly projecting annular 100 flange 54 adapted to form an abutment for the uppermost coil 55 of spring 52. The lowermost coil 56 of the spring 52 engages against the shoulder 57 formed in the hollow socket 49, and it is seen that when the handle 105 47 is drawn downward to the dotted position 58, the spring 52 is compressed until the cylindrical coils thereof lie approximately one upon the other, between the two abutments 54 and 57. Upon release of the 110 handle 47, the spring 52 automatically returns same to the retracted position 62, with the annular collar 59, which is rigidly mounted on the pipe 44, and the fiber or leather annular washer 60 engages the lower 115 end 61 of the socket 49, thereby forming a vertical "stop" for said handle 47. The fiber or leather washer 60 prevents noise, and reduces the shock when the handle returns automatically to the retracted position 120 125 130

62. When the handle 47 is withdrawn to 58 it will be noted that the parts 44, 49, 52, etc., are made of proper proportions so that the annular flange 54 of the cap 48 engages the 5 top 63 of the socket 49 as indicated at 64, to take the full load of the person, and form an unyielding support, similar to the function of the collar 16 and shoulder 22 of Fig. 5, before described. The modified type of 10 hanger 65 is mounted on the longitudinal tubular member 1, in similar fashion to the preferred form of stabilizer illustrated in Fig. 2. That is to say the member 43 is rotatably mounted in supports 2, Fig. 2, and 15 by operating a lever similar to 26 on the rod 43, the hanger 65 takes the angular or dotted positions 67, or 68 as shown in said Fig. 2. While I have shown in Fig. 4 only one stabilizer 33, and one locking device 69, it is 20 evident that a plurality of each may be mounted on the rod 1 when necessary. Attention is called to the convenient method of inserting new springs 52, and 14 in either 25 form of the device, as indicated by 65 or 66 of the drawings. The caps 48 and 11 need only be unscrewed from the members 44 and 7 respectively in order to replace wornout springs, or to dismount the members 44 or 7 for cleaning and oiling 30 purposes.

In the diagrams, Fig. 8 shows a "center entrance" type of electric car or other conveyance, with doors at 70, 71 as shown, the location of the "conductor" being indicated 35 at 72. On the longitudinal rods 35 to 38 inclusive are a plurality of stabilizers 73, 74, etc., which last may be of either of the types 65, or 66 or both. On the ends of the rods 35, 36, etc., are the locking devices 75, 76, 77, 78, similar to 69 before described. To illustrate the control of the loading of the car by the conductor, by an example, let it be supposed that all the seats in the car have been occupied, and all the 45 stabilizers 73, 74, etc., are in the angular positions 34 of Fig. 3, and locked by the lever 26 in position 79. The carman can then disengage lever 77 from its arcplate, and turn all the stabilizers 74 on the rod 50 38 into vertical and operative positions as at 80 of Fig. 3. Then all persons entering the car will naturally go to the point in the car where there are available stabilizers, to wit, those on rod 38. So that the carman 55 need not release any of the stabilizers on the other rods 35, 36, 37, until all those on rod 38 are in actual use. In this way as each 60 series of hangers or stabilizers on the various rods are required, the conductor places them in operative positions by means of the levers 75, 76, etc. By this means it is at once seen that all the standing room or 65 space in the car will be fully used, and the passengers will not become clustered around the doors of the car, "move up front" signs

will become obsolete, and each car can be loaded to capacity. The loading and unloading time of cars can also be shortened due to the passengers being in properly distributed positions, and ingress and egress 70 will be greatly facilitated. In Fig. 9 I have shown the "end entrance" type of car, the doors being at 81, 82. In this case the longitudinal rods 39 to 42 inclusive may be formed in four or more sections. So that 75 rods 39, and 41, 40 and 42 are separated at 83 and 84 respectively. The hangers 85 are used as before, and the locking devices as 80 at 86 to 89 inclusive, similar to 69 above described. In this case the conductor at 90 85 preferably operates two series of hangers on rods 39 and 40, while the motorman at 91 operates those on rods 41 and 42. In some cases where the cars are of a short length it may be found advantageous to have the 90 rods 39 and 41 continuous on both sides of the car, and entirely operated by the conductor. In both types of cars, especially where the "pay as you leave the car" method of collecting fares is used, it is seen that the 95 intelligent and sectional distribution of the passengers in the car by means of my invention is a very important matter, when the time consumed in loading cars, and the utilization of all the standing space in cars 95 is considered.

I claim:—

1. In a stabilizing device, in combination with a longitudinal supporting rod, a plurality of stabilizers mounted thereon, and 100 means for placing said series of stabilizers simultaneously into operative positions.

2. In a stabilizing device in combination with a rotatable longitudinal supporting member, a plurality of stabilizers mounted 105 thereon, a holder adapted to receive the rotatable member, an arc-plate on the holder provided with a number of slots, and a lever on the rotatable member having a projection engaging the said slots, for placing the stabilizers into operative positions.

3. In a stabilizing device, a rotatable longitudinal member, a plurality of automatically retractable stabilizers mounted on same, and means for placing a series of stabilizers simultaneously into operative positions.

4. In a stabilizing device, a rotatable longitudinal member, a stabilizer having an extensible handle slidably mounted in said 120 member, resilient means for retracting the stabilizer handle, and means for placing the stabilizer into operative position.

5. In a stabilizing device, a longitudinal member, a casting mounted on the same having a flange adapted to receive the coil of a spring, and a downwardly projecting tubular portion, a vertically disposed pipe having a handle slidably mounted in the latter, an annular stop on the lower end of 130

the vertical pipe, a cap on the upper end of same, and resilient means for retracting the aforesaid handle when not in use.

6. In a stabilizer, a casting having an upwardly turned flange adapted to receive the coil of a spring, a downwardly projecting tubular portion formed on the casting, a vertical pipe having a handle thereon slidably mounted in the tubular portion of the 10 said casting, means forming a stop carried on the lower end of the vertical pipe a cap on the latter having a downwardly turned flange adapted to receive the coil of a spring, and resilient means engaging the flanges of 15 said cap and casting for retracting the aforesaid handle when not in use.

7. In a stabilizer, a casting having a flange with an upwardly turned rim, an annular bossed shoulder on the said flange, a 20 downwardly projecting tubular member formed integral with the casting, an extensible vertical pipe forming a handle, and slidably operable within the tubular member, a cap on the upper end of the vertical pipe 25 having a downwardly turned rim, a tapered spiral spring engaging the rims of said cap and casting, and an annular collar on the vertical pipe for engaging the bossed shoulder of the casting and limit the downward 30 extension movement of the aforesaid stabilizer handle.

8. In a stabilizer, a casting having an outwardly extending flange, and a downwardly projecting tubular portion, a vertical pipe 35 reciprocally operable within the latter, a cap

on the upper end of the vertical pipe, and means for resiliently resisting the downward extension movement of the aforesaid vertical pipe.

9. In a stabilizer, a longitudinal tubular 40 member, a vertically disposed pipe provided with a handle on its lower end, slidably operating within the first member, and resilient means interacting between the pipe and the tubular member for retracting the aforesaid handle when not in use. 45

10. In a stabilizing device, a longitudinal supporting rod, a vertical member mounted in the former, a vertically disposed pipe provided with a handle on its lower end, slidably operating within the latter member, and resilient means interacting between the pipe and vertical member for retracting the aforesaid handle when not in use. 50

11. In a stabilizing device, a longitudinal 55 supporting rod, a vertical member mounted on the former, a vertical pipe provided with a handle slidably operating within the latter member, resilient means interacting between the pipe and vertical member for re- 60 tracting the handle automatically when not in service, and means for placing the vertically disposed member into operative position.

In testimony whereof I affix my signature 65 in the presence of two witnesses.

FRED D. BLESSMEYER.
